HAT SWEAT BAND

Leslie M. Page, New York, N. Y., assignor to
Beatty-Page, Inc., New York, N. Y., a corpora-
tion of New York

Application May 13, 1936, Serial No. 79,416

1 Claim. (Cl. 2—181)

This invention relates to hats, and particularly to the sweat band thereof.

The various sweat bands, known or used heretofore, possess serious disadvantages in that they fail to provide ample protection for the hat and produce irritation to the wearer, thereby causing considerable spoliation and much discomfort. These disadvantages are particularly enhanced during warm weather or in warm rooms, when 10 perspiration is increased.

The principal object of my invention is to provide an improved sweat band which will remedy the above mentioned disadvantages, and provide improved protection for the hat and improved comfort for the wearer.

Other objects and advantages will hereinafter appear.

In the accompanying drawing,—

Fig. 1 is a fragmentary cross-sectional elevation 20 of a hat body and of the sweat band of this invention, as it appears when assembled with the hat body.

Fig. 2 is a cross-sectional elevation, on an enlarged scale, showing a portion of the sweat band.

Fig. 3 is a fragmentary cross-sectional elevation 25 of the sweat band in completed or assembled state, as it appears prior to its installation in the hat body.

Fig. 4 is a view showing a part of the elements 30 comprising the sweat band, during assemblage.

Figs. 5, 6, 7 show modifications of the invention.

The sweat band 1 comprises an interior wall 2 consisting of canvas or any other similar or suitable textile or material, the function of which is to lend erectile body to the hat band and to act as an absorbent for the perspiration. On its inner side the wall 2 is lined with a layer 3 of textile fabric material, which will be pervious 35 to perspiration and impart smoothness and comfort of the wearer, such material being rayon, silk, or any other material possessing such requisite properties. The layer 3 has hem 4, 5 passing around and enveloping the upper and lower edgings 6, 7 respectively of the wall 2. In assemblage of these parts, the edge of layer 3 is stitched at 8 to edge 6 of the wall 2, in the manner shown in Fig. 4, then the material of the layer 3 is passed around the edge 6 and against the inner side of wall 2 to form the hem 4, and then the hem 5 is formed, unstitched or unattached to the wall 2, by passing the opposite edge of the layer 3 around the lower edge 7 of wall 2. At the outer side of the wall 2 is located a layer of rubberized 40 fabric 9, or any other similar or suitable imper-

vious material. The layer 9 is provided at its lower edging with a hem 10, and in the assemblage of the sweat band a stitching 11 is passed clear through the hem 10 of the layer 9, the hem 5 of the layer 3, and the enveloped edging 7 of wall 2, as shown in Fig. 3, whereby upon completion of the assemblage of the sweat band there is provided a downhanging portion 12 of the hem 10 of layer 9 projecting below the lower terminal edge 13 of the sweat band 1 proper. In the general assemblage of the sweat band 1 with the hat 14, a stitching 15 is passed through the latter and through the projecting portion 12 of downhanging hem 10 of the band, as illustrated in Figs. 1, 2, to secure the sweat band in operative state within 15 the hat.

During the wearing of the hat equipped with this sweat band, the perspiration as soon as formed at once penetrates the pervious layer 3 and is absorbed by the interior wall 2, and any 20 dampness developing in the wall 2 is prevented from reaching the material of hat 14 by the intervening impervious layer 9, which is thus interposed between the hat and the other layers constituting the sweat band. There is thus maximum dryness, coolness, and comfort afforded to the wearer by this sweat band, without causing any injury or spoliation of the hat body. It will be evident that even in cool situations, or when 25 no perspiration whatever is formed, this hat band 30 by virtue of the combination of its elements will provide maximum ease, softness, and comfortable feeling to the wearer. The projection of hemmed portion 12 of impervious layer 9 below terminal edge 13 of the hat band proper and its attachment thereat to the hat body will efficiently insulate the hat material thereat against any dampness or saturation that may occur at the lower 35 terminal edge of the sweat band.

According to the modification shown in Fig. 5, 40 the interior canvas wall 2 and inner fabric 3 are firmly cemented to each other by a cementitious layer 16, as illustrated, by means of which additional rigidity or erectile body is imparted to the sweat band.

In the modification shown in Figs. 6, 7, a stitching 17, instead of penetrating clear through all the material like stitching 11, does not pass through the inner textile layer 3. In the manufacture of this sweat band, the stitching 17 is passed through 50 the hem 10 of layer 9, and the lower edges of layer 3 and canvas wall 2, as shown in Fig. 6. And then the attached layer 3 and wall 2 are swung upwardly and about the stitching 17 to the assembled position shown in Fig. 7, thereby 55

producing the lower hem 5 of layer 3 and creating a hem 18 upon wall 2. In this sweat band, therefore, any formation of perspiration upon the lower part of layer 3 is prevented from accidentally reaching the stitching 17 or therethrough to the hat body 14, such moisture being at once absorbed by the canvas 2 thereat.

Variations may be resorted to within the scope of the invention, and portions of the improvements may be used without others.

Having thus described my invention, I claim:—
A hat sweat band having the combination of an

interior wall consisting of an absorbent material, an inner layer upon said wall for contact with the wearer consisting of a pervious material, an outer layer upon said wall disposable against the hat consisting of an impervious material, said outer layer having its lower portion hemmed, said lower hemmed portion of said outer layer projecting below the lower edges of said wall and inner layer, and a stitching passing through said lower hemmed portion, said wall, and said inner layer. 5 10
